TURBINE NOZZLE STRUCTURE

John E. Corr, Scotia, and Joseph H. Ouellette, Albany, N. Y., assignors to General Electric Company, a corporation of New York

Application December 6, 1951, Serial No. 260,229

5 Claims. (Cl. 253—78)

This turbine relates to elastic fluid turbines, particularly to the construction of the nozzle member used to direct the motive fluid into the buckets of the moving wheel.

As will be appreciated by those familiar with the steam turbine art, nozzles and diaphragms ordinarily are fabricated largely by welding, from a comparatively heavy plate member having at least one arcuate opening through the outer circumferential portion thereof, in which opening are disposed a pair of radially spaced arcuate bands suitably sealed and secured to the disk member and having a plurality of circumferentially spaced airfoil-shaped "partitions" or blades extending radially across the arcuate nozzle passage defined between the bands. Nozzle diaphragms of this general type and arrangement are disclosed, for instance, in the United States patents to Haigh—2,373,558 issued April 10, 1945, and 2,264,877 issued December 2, 1941, and the patent to Truex—2,245,237 issued June 10, 1941.

In the modern high-temperature, high-pressure steam turbine, the nozzle partitions are subjected to substantial bending stresses due to the pressure differential existing across the partitions in normal operation. The stresses in the partitions are further increased by any residual stresses remaining from the welding operation and by differential thermal expansion which takes place between the comparatively thin blades and the relatively massive bands and adjacent disk portions. This problem is particularly serious in the very thin exit edge portions of the nozzle blades. If these thin discharge edge portions are rigidly fixed to the bands, then when loaded by the pressure differential across the partitions, they behave as a beam fixed at both ends. This loading, taken with the differential thermal expansion stresses, may very well produce failure in the thin exit edges of the blades unless special means are provided for permitting some elasticity in the end portions of the blade so that it does not behave as a beam fixed at both ends. The construction described herein provides elasticity or freedom for the partition discharge edges so that the high stresses which otherwise occur in conventional constructions do not appear.

Accordingly, the object of the present invention is to provide an improved nozzle diaphragm structure, arranged to provide such elasticity in the means for securing the blades to the bands as to prevent over-stressing of the thin exit edge portions of the blades.

Other objects and advantages will become apparent from the following description taken in connection with the accompanying drawings, in which Figure 1 is a longitudinal section through the outer circumferential portion of a nozzle diaphragm incorporating the invention, Figure 2 is a cross section of a single nozzle blade, taken on the plane 2—2 in Figure 1, Figure 3 is a side view in elevation of a blade, Figure 4 is an end view of the blade taken in the direction 4—4 in Figure 3, Figure 5 is a perspective view of one blade by itself, and Figures 6 and 7 are detail views of two possible modifications.

Generally stated, the invention is practiced by using comparatively thick arcuate bands which are welded to

the adjacent portions of the diaphragm disk. Each blade is provided with comparatively massive root and tip portions with special slots arranged to introduce flexibility at the trailing edges of the blades.

Referring now more particularly to Figure 1, the invention is disclosed as applied to a diaphragm disk 1 defining an arcuate nozzle inlet passage 2 and having an outer circumferential portion 1a adapted to be received in a suitable circumferential groove in the turbine casing (not shown). The nozzle structure proper comprises spaced arcuate bands 3, 4 firmly secured by comparatively massive welds 5, 6 respectively to the adjacent portions of the disk 1 to form wall portions of the nozzle passage. The inlet portions of the bands 3, 4 are sealed against fluid leakage by smaller concentric circumferential welds 7, 8.

The nozzle blade comprises an airfoil-shaped intermediate portion 9 with a root section 10 and a tip section 11. The configuration of each nozzle blade is shown in Figures 2, 3, 4, and the perspective view in Figure 5. The thickened root and tip portions 10, 11 are provided because of the extreme difficulty which would be experienced in trying to machine in the comparatively massive bands 3, 4 a hole having the precise configuration of the airfoil portion 9 with its extremely thin exit edge 9a.

In accordance with the invention, the required degree of flexibility is provided in the blade attachment by axially slotting the thickened root and tip portions 10, 11. These slots may be conveniently formed by drilling transverse holes shown at 12, 13 respectively and then cutting apertures through from the edge as indicated at 12a, 13a respectively.

As will be apparent from the assembly view shown in Figure 1, the outer portions of the bands 3, 4 are firmly secured by the massive welds 5, 6. On the other hand, by reason of the presence of the holes 12, 13, and apertures 12a, 13a the comparatively thin exit edge portion 9a of the airfoil section 9 is substantially free to deflect radially of the nozzle inlet passage to a limited extent. Thus elastic deformation of the exit edge of the blade prevents the creation of stresses sufficient to cause cracking and eventual failure. At the same time, the thickened portions 10, 11 of the discharge edge serve to prevent the thin trailing edge 9a of the blade from "fluttering" since these enlarged blade portions fit the cooperating openings machined in the bands 3, 4. As shown in Fig. 1, the thickened end portions of the blade, at the sides of the holes 12, 13 remote from the thin vane edge 9a, are fused to the band members 3, 4 to positively locate the blades relative to the bands.

In connection with the detailed design of a nozzle diaphragm incorporating the invention, it may be noted that, with bands of a thickness on the order of $\frac{5}{8}$ ", it is considered that the minimum diameter of the holes 12, 13 should be on the order of $\frac{3}{4}$ ". It will be seen from Figure 1 that welds 7, 8 effectively prevent leakage of motive fluid around the outside of the bands 3, 4 while the welds 5, 6 seal against leakage radially outward between the blade end portions 10, 11 and the cooperating surfaces of the openings formed in the bands.

Thus it will be apparent that the invention provides a simple and rugged nozzle diaphragm construction which is effectively sealed against leakage and incorporates the degree of resiliency required to prevent excessive stresses in the thin trailing edges of the blades.

While only one embodiment of the invention has been described specifically, it will be apparent to those skilled in the art that many minor alterations and substitutions of mechanical equivalents may be made. For instance, in some applications it may be found that only one end of the blade need be slotted, as illustrated in Fig. 7, in order to give the required degree of flexibility. Further-

more, the required flexibility in the connecting means for the thin discharge edges of the blades may be provided in other equivalent ways. Figure 6 shows one of these. In this modification, the blade 9 is exactly as shown in Figure 5, except that the means for expansion consists of having the corner of the thickened root or tip portion sawed away, as indicated by the curved separation surface 11a to form a clearance space or recess 11c. The detached insert portion 11b is loosely placed in the slot in band 3 during the welding operation, so that the weld metal 5 becomes fused to the separate portion 11b, leaving the remaining thickened edge portion 11c completely free to expand and contract radially relative to the nozzle inlet passage of the welded portion. The process of sawing off the portion 11b will of course remove enough metal to insure that there will be a small clearance space as shown at 11d. This modification is substantially the mechanical equivalent of the blade form illustrated in Figures 1-5. Other equivalents will occur to those skilled in the art.

It is of course intended to cover by the appended claims all such modifications as fall within the true spirit and scope of the invention.

What I claim as new and desire to secure by Letters Patent of the United States is:

1. A turbine nozzle structure including a first member provided with an arcuate nozzle passage extending axially therethrough, a pair of radially spaced arcuate band members fused to the first member to form radially spaced inner and outer wall portions of the nozzle passage, and a plurality of circumferentially spaced nozzle blades extending radially across the nozzle passage, each blade having a thin exit edge portion, the root and tip portions of each blade being thickened adjacent the exit edge and occupying recesses of similar shape in the respective band members, said thickened edge portions within the confines of said recesses each being provided with an axial slot extending inwardly a substantial distance from the extremity of the thickened edge, whereby said thin blade edge portion is free to expand and contract in a direction radially of the nozzle passage.

2. A nozzle structure in accordance with claim 1 in which the slot in the thickened edge portion comprises a transverse drilled hole communicating with an aperture of an axial width less than the diameter of the hole and extending through the discharge edge of the blade.

3. A turbine nozzle structure including a first member adapted to be disposed transversely in a turbine casing and provided with an arcuate nozzle passage extending axially therethrough, a pair of radially spaced arcuate

band members fused to said first member to form radially spaced inner and outer wall portions of the nozzle passage, and a plurality of circumferentially spaced nozzle blades extending radially across the nozzle passage, each blade having a thin exit edge portion, the root and tip portions of each blade being thickened adjacent the exit edge and occupying recesses of similar shape in the respective band members, the extreme ends of the root and tip portions of said blades being fused to their cooperating band members, at least one of said thickened edge portions being provided with an axially extending separation surface spaced radially between the adjacent wall portion of said nozzle passage and the fused ends of the blades, said separation surfaces extending inwardly a substantial distance from the exit edge, whereby said thin blade edge portion is free to expand and contract in a direction radially of the nozzle passage.

4. A turbine nozzle structure including a first member adapted to be disposed transversely in a turbine casing and provided with an arcuate nozzle passage extending axially therethrough, a pair of radially spaced arcuate band members fused to said first member to form radially spaced inner and outer wall portions of the nozzle passage, and a plurality of circumferentially spaced nozzle blades extending radially across the nozzle passage, each blade having a thin exit edge portion, the root and tip portion of each blade being thickened adjacent the exit edge and occupying a recess of similar shape in the respective band members, the extreme ends of the root and tip portions of the blades being fused to the respective band members, said thickened edge portions within the confines of the recess in said band member each being provided with a second recess extending axially and proceeding inwardly a substantial distance from the exit edge, whereby said thin blade exit edge portion is free to expand and contract in a direction radially of the nozzle passage, and a separate insert member fused to the adjacent band member and disposed in each of said second recesses but spaced from the nozzle blade to form a clearance space.

5. A nozzle structure in accordance with claim 4 in which the inserts disposed in the recesses of the thickened blade edge portions, have the same external contour as the thickened edge portions of the blade.
